UNITED STATES PATENT OFFICE.

HOMER H. GEE, OF LYONS, MICHIGAN.

TOY WATER MILL.

Application filed July 7, 1925. Serial No. 42,063.

This invention relates to mechanical toys and has for its primary object the provision, in a manner as hereinafter set forth, of a water operated toy or wind mill, in which the water is led from a compartment in the upper portion of a building to and over a water wheel mounted at one side of the building. The water operating the wheel is caught in a tray positioned therebeneath which tray is removable so that the water caught thereby can be replaced in the reservoir located in the upper portion of the mill house to pass over the wheel again.

The invention contemplates the provision of a toy house formed with an upper and lower compartment, the upper compartment being water tight and adapted to be filled with water through the chimney of the house. Leading from this upper compartment is a relatively small tube which extends out and overlies a water wheel revolvably mounted at one side of the house. An enclosure is formed at one side of the house beneath the water wheel and this enclosure is designed to receive a removable tray or pan which catches the water which passes over the wheel to operate the same and when filled this pan can be removed and the water therein poured back into the reservoir in the upper chamber of the house to pass through the same circuit again.

A further and final object of this invention is the provision, in a manner as hereinafter set forth, of a novel and attractive water operated toy which will be strong and durable, easily operated by a child, devoid of all features which would make it dangerous for use by a child, and inexpensive to manufacture.

The invention will be best understood from a consideration of the following detailed description taken in connection with the accompanying drawings forming a part of this specification, with the understanding that the invention is not confined to any strict conformity with the showing of the drawings but may be changed and modified so long as such changes and modifications mark no material departure from the salient features of the invention as expressed in the appended claim.

In the drawings:—

Figure 1 is a side elevation of the toy embodying this invention.

Figure 2 is a top plan view of the same,

a portion thereof being broken away to show certain details of construction.

Figure 3 shows a section taken longitudinally through the water pan and holder therefor, showing the water wheel and part 60 of the house in elevation.

Figure 4 is a section taken transversely through the lower portion of the house and through the water pan and,

Figure 5 is a longitudinal section, upon a 65 small scale, through the upper portion of the mill house.

Referring now to the drawings in detail wherein like numerals of reference indicate corresponding parts throughout the several views there is indicated generally by the numeral 1 a miniature building of substantial height and having the front and back walls 2 and 3, and the side walls 4 and 5 as is shown.

This miniature house is provided with a sloping or hip roof 6, in the central portion of which is positioned a chimney 7 which opens into the interior of the house.

Secured within the house and between the four walls thereof, is a partition or floor 8 which divides the building into an upper and lower chamber 9 and 10 respectively. This floor or partition 8 is secured to the four walls of the building in such a manner as to 80 be water-tight so that the upper chamber 9 can hold a quantity of water.

At one side of the building 1, here shown as the side 4, there is constructed an enclosure indicated generally by the numeral 90 11. This enclosure comprises a bottom portion 12 which extends beneath the bottom of the house 1 and is secured thereto and extending upwardly from the rear and side edges of this bottom 12 are the back and 95 side portions 13 and 14 respectively of the enclosure. The side portion 14 of the enclosure, as shown clearly in Figures 1 and 2 extends a substantial distance beyond the front of the house 1 to provide the extended 100 tapered off portion 15. A brace member 16 is extended diagonally across the corner of the enclosure 11 between the side and back portions as is shown in Figure 2.

Journalled in and between the wall 4 and the side 14 of the enclosure is a revoluble shaft 17 carrying at its central portion the wheel 18 from the periphery of which the transversely positioned paddles 19 extend.

Leading from the chamber 9 in the upper 110

portion of the house 1 is a water conveyor tube 20 which leads around and overlies the upper portion of the enclosure 11, the forward terminal end portion being down turned as indicated at 21 and overlying the forward portion of the paddle wheel 18. The tube 20 has a slight inclination downwardly so that water may be led by gravity from the compartment 9 to contact with the 10 paddles 19 upon the paddle wheel.

For the reception of the water flowing over the paddle wheel 18, there is provided a tray or pan of substantial depth as indicated at 22. This pan is a relatively long 15 receptacle and is designed to fit into the enclosure 11, one end of the pan extending beyond the open front portion of the enclosure for easy removal therefrom.

It will be seen that upon pouring water 20 through the chimney 7 to fill the receptacle 9 the fluid will flow through the tube 20 and falling upon the paddle wheel 18 will cause the same to revolve. The water passing over the paddle wheel will be caught 25 within the pan 22 and when the same has been filled it can be removed and the contents thereof poured back through the

chimney 7 into the receptacle 9 to pass through the former course.

Having thus described my invention what I claim is:—

A toy of the character set forth comprising a miniature house, a floor partition within the upper portion of said house setting up a water chamber, an enclosure having a rear wall extending from the back wall of said house and a side wall extending from said rear wall transversely of the house and extended a substantial distance beyond the front thereof, a revoluble shaft 40 extending transversely of said enclosure and having one end mounted in said house and the other end mounted in said side wall, a paddle wheel carried by said shaft, a water pipe leading from the interior of said chamber to and terminating over said wheel, and a removable receptacle positioned to receive water discharged over said wheel and held in position therebeneath by the side and rear walls of said enclosure and the end wall of 50 said house.

In testimony whereof, I affix my signature hereto.

HOMER H. GEE.
